Primary Examiner — Philip S Hyder*Assistant Examiner* — Ryan Harvey(74) *Attorney, Agent, or Firm* — Muncy, Geissler, Olds & Lowe, P.C.(57) **CLAIM**

The ornamental design for a gaming machine, as shown and described.

DESCRIPTION

FIG. 1 is a perspective view of a gaming machine showing the new design;

FIG. 2 is a front view of the new design;

FIG. 3 is a rear view of the new design;

FIG. 4 is a left view of the new design;

FIG. 5 is a right view of the new design;

FIG. 6 is a top view of the new design; and,

FIG. 7 is a bottom view of the new design.

The broken lines are for the purpose of illustrating portions of the gaming machine which form no part of the claimed design.

1 Claim, 7 Drawing Sheets(56)
